UNITED STATES PATENT OFFICE

2,293,982

MANUFACTURE OF RAYON

Arthur L. Jackson, West Asheville, N. C., assignor
to American Enka Corporation, Enka, N. C., a
corporation of Delaware

Application April 19, 1940, Serial No. 330,596

6 Claims. (Cl. 34—153)

This invention relates to the treatment of continuous filaments, yarns, threads and the like, and more particularly to apparatus for heating and drying succeeding portions of such materials.

While it will be readily recognized that this invention is applicable to and of considerable importance in the various arts and industries in which the heat treatment of succeeding portions of a continuous material is a problem, regardless of whether such materials be in strip, band or thread form; it is of even greater importance in the rayon industry where it may be employed as a very valuable adjunct to the various liquid treatment operations to which rayon threads are subjected in the course of their manufacture.

It has long been customary to subject artificial filaments to a drying operation after the completion or intermediate the various liquid treatments incident to their manufacture. However, the prior practice employed in performing this operation usually involved the extrusion and coagulation of the cellulosic material followed by the winding of the same into a yarn package or cake. The package was then treated with various liquids and finally subjected to an atmosphere suitable for effecting the drying of the component yarn thereof. As a result of this practice, early developments with respect to the drying of rayon threads were largely concerned with either the preparation of apparatus for the production of suitable drying atmospheres for the treatment of the thread package or the preparation of the package itself in such a way that the thread composing the same might be treated and dried as efficiently and as uniformly as possible.

In recent years, the demands of the various arts in which rayon threads are used have become progressively more severe and the new criteria as to strength and uniformity are difficult of attainment by the employment of the older type methods and apparatus. To meet these demands, extensive changes have been made in the processes and apparatus for the manufacture of rayon, so that it is now possible for a continuous yarn to be passed in succession, without interruption or intermediate collection, from a spinneret to a number of thread-storage, thread-advancing devices in association with each of which the thread is subjected to one or more treatments which may be in the form of liquid baths, liquid sprays or drying operations, and finally to a collecting device on which it is wound in a form suitable for shipment to the consumer.

The thread-storage, thread-advancing devices on which rayon is treated during the course of

its manufacture may take a number of forms and may be supported from either one or both ends. It has been found, however, that a cantilever support is quite desirable in that, incident to its use, threading up is facilitated and attendance of the machine by the operator is rendered more convenient. The continuous spinning development as a whole has met with outstanding success and, as a result of the adoption of the new system, improved materials are producible while operating costs have been reduced.

It will be recognized that it is quite important, if the advantages of the continuous spinning processes are to be exploited to the fullest extent, that the entire treatment of the thread be accomplished in a continuous manner without intermediate packaging for any steps, even for the final step of drying. The reason for this is that reversion to the old treating systems, even in part, will result in a return to the very disadvantages of such systems which continuous spinning is designed to avoid. Thus, it is necessary that a drier, which will dry succeeding portions of a continuous filament upon completion of the various prior steps, form a component part of each continuous spinning system.

Several such driers have been developed and they more or less parallel in form and operation the thread-storage, thread-advancing devices used in conjunction with liquid treatment. However, driers of this character, as known today, are characterized by one or more disadvantages. Either the heating means is satisfactory insofar as the treatment of the thread is concerned while the means for applying the heat to the thread-storage, thread-advancing device is cumbersome and inefficient; or else the heat supplying means is satisfactory, but the thread contacting means is modified in such a way as to interfere with other portions of the spinning apparatus.

This invention contemplates overcoming all of the difficulties outlined above, and involves the drying of rayon or other thread quickly, efficiently and at uniformly controlled temperatures by the employment of apparatus which is cheaper to construct, easier to control and superior in performance to devices heretofore known and used for the same or similar purposes.

It is an object of this invention to provide a drier in which a thread contacting member may be immediately supported at one end only thereof and a heating fluid may be supplied to an interior cavity of the contacting member through the other end thereof. By this arrangement, the many advantages of the cantilever type reel may

be retained while the use of complicated and inefficient packing glands surrounding the feed tubes and drain tubes of driers known to the prior art may be avoided.

According to this invention, the heating fluid supplied to the thread contacting member may be furnished and withdrawn at any rate deemed desirable, while the contacting member itself is light, thin and strong for efficient heat exchange and easy operation.

This invention further contemplates the provision of a thread contacting member over which thread may be drawn to be dried in heat exchange relationship therewith. While the thread contacting member may be either driven or freely rotatable, the means for supplying and withdrawing heating fluid therefrom are stationary, and consequently do not have to be provided with the elaborate leak-preventing means which are normally associated with a driven shaft around which, or along which, fluids are caused to pass.

While it will be recognized that this invention has wide applicability to all types of drying operations wherein a continuous filament, thread or the like is passed across a heating member, the present development is of particular value in connection with and as an adjunct to the continuous spinning methods and apparatus constituting the subject-matter of Adrian J. L. Moritz et al. application, Serial Number 322,386, filed March 5, 1940.

Other objects and advantages of the invention will be apparent from a consideration of the following detailed description in conjunction with the annexed drawing wherein:

Figure 1 is a view in elevation of a preferred form of a thread-storage, thread-advancing device constructed according to the present invention;

Figure 2 is a view partially in section showing the interior construction of the heated roller constituting a part of the thread-storage, thread-advancing device; and

Figure 3 is a view taken along the line 3—3 of Figure 2.

The thread-storage, thread-advancing device shown in Figure 1 is of cantilever construction and may constitute one of a series of such devices on which thread 10 is treated in its passage from a spinneret to a collecting device. To support the various thread-storage, thread-advancing devices constituting the machine, a frame 11 is provided, a portion of which is shown in Figure 1. Extending upwardly from a projection 12 of frame 11 is a channel bar 13 fastened at its upper end to a transverse piece 14.

Channel bar 13 is the supporting member for hollow roller 15 and roller 16 which together constitute the thread-storage, thread-advancing device. Roller 15 is provided with an end piece 17 which seals one end thereof and to which a shaft 18 is keyed. Shaft 18 passes through and is journaled in bracket 19, affixed to channel bar 13. An end of shaft 18 extends beyond bracket 19 and has fixed thereto a bevel gear 20.

Roller 16 is supported in a manner similar to roller 15, shaft 21 being keyed to roller 16 and extending through channel bar 13 to a bracket 22 mounted upon a rotatable shaft wherein it is suitably journaled.

It will be noted that rollers 15 and 16 have their axes, shafts 18 and 21 respectively, in converging relationship. Thread 10, when passed over the rollers as shown in Figure 1, will be fed axially of the thread-storage, thread-advancing

device in a direction toward the unobstructed ends of the rollers. Because of the manner in which the thread is fed, it passes across any given thread-storage, thread-advancing device in a generally helical path, contacting each roller a plurality of times. The shafts are mounted for relative adjustment for the purpose of permitting the control of the feed on the thread and the spacing of the helices. This may be accomplished by the pivotal adjustment of the mounting 22 in which shaft 21 is journaled. For this reason it is customary to drive only one of the rollers constituting the device, the other roller being driven by the thread passing therearound. Thus, roller 15 is provided with bevel gear 20 which meshes with a gear 23 keyed to shaft 24 which is driven and supported in a manner not shown. The motion imparted to roller 15 will, through thread 10, drive roller 16 which is journaled for free rotation in bracket 22.

In order to heat and therefore dry the thread passing across roller 15 a pipe 25 is provided, the nozzle 26 of which discharges in the hollow interior cavity defined by the cylindrical walls 25 of roller 15 and piece 17. This pipe is stationary and may be attached in any feasible manner to a suitable portion of the supporting structure. It is important that the pipe 25 be firmly held so that it may maintain its axial position in roller 15 without striking against either shaft 18 or the annular baffle 27 which extends radially inwardly from the cylindrical walls of roller 15 at the unsupported end thereof to function as a dam. Annular baffle 27 is provided with a flared lip 28 which leads into an arcuate trough 29 affixed to the channel bar 13. A drain pipe 30, supported in any suitable manner from the machine frame, leads from the lowest point of trough 29.

When it is desired to dry thread 10 on the thread-storage, thread-advancing device shown in the annexed drawing, shaft 24 is driven so that, through gears 23 and 20, shaft 18 and roller 15 will be caused to rotate. Thread 10 is then passed around rollers 15 and 16 in a generally helical path. Said thread is then fed toward the unsupported end of the device where it is drawn off and either collected or passed to another treating device. A heating fluid such as hot water is passed through pipe 25 and ejected into the hollow interior of roller 15 through nozzle 26. The fluid will collect in the bottom of the roller as shown in Figure 2 until the level is raised to such an extent that an overflow of fluid will occur over annular baffle 27, across lip 28 and into trough 29 from which it will drain by gravity through drain 30. The liquid issuing from drain 30 may be either reheated and recirculated through pipe 25 or else permitted to waste.

Because of the fact that roller 15 is rotating during the time that the heating liquid is passed therein through pipe 25 and flows therefrom over baffle 27, a thin film of hot liquid will adhere to the interior surface of the cylinder to assist in the maintenance of the roller at the temperature of the heating fluid. In view of the fact that roller 15 is supported entirely from the free or unobstructed end by virtue of the keyed connection between shaft 18 and end piece 17, the walls of the cylinder themselves may be quite thin. This, of course, favors heat exchange through such walls so that the amount of heat imparted to the thread 10 in its passage across the roller 15 can be accurately controlled by controlling the temperature of the water entering through pipe 25 and nozzle 26. The amount of water trapped

in roller 15 may be controlled by modifying the width of annular baffle 27 although it is generally desirable for the baffle to be about as high as is shown in Figure 2 so that a good volume of water will be available to maintain a given temperature. It will be recognized that the heating means disclosed is equally applicable with respect to a freely rotating roller such as roller 16. In this instance, it may be desirable to have baffle 27 a little lower so that the amount of trapped liquid and consequently the weight of the roller as a whole may be less. In the event a freely rotatable roller is to be heated, the advantage in supporting the roller from its unobstructed end in the manner disclosed is emphasized since the use of light materials in such a case is quite desirable. It is, of course, to be understood that the rollers 15 and 16 may, if desired, be conically shaped. When such conical rollers are employed the delivery of the fluid into the roller to be heated, and the drainage of the used liquid therefrom, may be accomplished in the same manner as described and illustrated in connection with the cylindrical rollers.

In some instances, both the driven and freely rotatable rollers may be heated and, in addition to heating only the thread passing across the thread-storage, thread-advancing device, liquids sprayed upon the threads may likewise be raised in temperature.

The above description of a preferred embodiment of this invention is but for purposes of illustration and it is not intended that the scope of the invention be limited beyond the spirit of the appended claims.

What is claimed is:

1. Thread drying apparatus comprising at least two rollers of cantilever construction at least one of which is hollow, said rollers having their supported ends wholly closed and exteriorly unobstructed, the rollers being mounted so that their axes are in non-parallel relationship to advance the thread laterally thereof in a generally helical path, means for introducing a heating liquid into the interior of the hollow roller through the unsupported end thereof and an outlet for said liquid.

2. Thread drying apparatus comprising at least two rollers of cantilever construction, at least one of which is hollow, each roller having one end wholly exteriorly unobstructed and supporting means attached to, and rotatable with, that end, the rollers being mounted so that their axes are in non-parallel relationship to advance the thread laterally thereof in a generally helical path, means for supplying a heating liquid to the interior of the hollow roller through the unsupported end thereof and an outlet for said liquid.

3. Thread drying apparatus comprising at least two rollers of cantilever construction, at least one of which is hollow, each roller having one end wholly closed and exteriorly unobstructed and supporting means attached to, and rotatable with, that end, the rollers being mounted so that their axes are in non-parallel relationship to advance the thread laterally thereof in a generally helical path, means for supplying a heating liquid to the interior of the hollow roller through the unsupported end thereof, means for retain-

ing a predetermined amount of the liquid within the roller and an outlet for excess liquid.

4. Thread drying apparatus comprising at least two rollers of cantilever construction at least one of which is hollow, each roller having one end wholly closed and exteriorly unobstructed and supporting means attached to, and rotatable with, that end, the supporting means of said hollow roller extending axially therethrough and attached only at the end of the roller remote from the point of entrance of said support, the rollers being mounted so that their axes are in non-parallel relationship to advance the thread laterally thereof in a generally helical path, means for supplying a heating liquid to the inner surface of the hollow roller through the unsupported end thereof, an annular baffle extending radially inwardly at the open end of said roller for retaining a predetermined amount of the liquid therein, and an outlet for liquid in excess of that retained by said baffle.

5. Thread drying apparatus comprising at least two rollers of cantilever construction, at least one of which is hollow, each roller having one end wholly closed and exteriorly unobstructed and supporting means attached to, and rotatable with, that end, the rollers being mounted so that their axes are in non-parallel relationship to advance the thread laterally thereof in a generally helical path, an annular baffle extending radially inwardly at the open end of the hollow roller, a stationary conduit extending into and adapted to discharge within the hollow interior and contact the inner surface of said roller, means for supplying heating liquid to said conduit, and stationary means disposed adjacent the baffle for receiving liquid issuing thereover.

6. Thread drying apparatus comprising two rollers of cantilever construction at least one of which is hollow and at least one of which is power driven, each roller having one end wholly closed and exteriorly unobstructed and supporting means attached to, and rotatable with, that end, the rollers being mounted so that their axes are in non-parallel relationship to advance the thread laterally thereof in a generally helical path, the other end of the hollow roller being unsupported and substantially open and having an annular baffle associated therewith, said baffle extending radially inwardly from the cylindrical wall, said supporting means comprising a shaft extending axially through said hollow roller and attached to the closed end only, means for driving said shaft, a stationary conduit extending into the interior of the hollow roller, a nozzle on said conduit adapted to discharge within said hollow interior, means for supplying a hot liquid to said conduit for ejection within said roller, and means defining an annular trough adjacent the open end of the roller and radially disposed therebelow, said trough being attached to a stationary support, whereby a cantilever thread-storage, thread-advancing device having heating means in at least one of the rollers thereof may be provided without interference with the unobstructed end and without the necessity for leak-preventing means associated with movable parts.

ARTHUR L. JACKSON.
